MARINE HORN

Harry R. Bingham, 1110 Polynesia Drive,
San Mateo, Calif. 94404

Filed Nov. 6, 1970, Ser. No. 25,861

Term of patent 14 years

Int. Cl. D29—02

U.S. Cl. D72—1

Fig. 8

FIG. 1 is a perspective view of a marine horn showing my new design;

FIG. 2 is a perspective view of the opposite side thereof;

FIG. 3 is a top plan view on a reduced scale;

FIG. 4 is a side elevational view thereof on a reduced scale;

FIG. 5 is a cross-sectional view taken along line 5—5 of FIG. 4;

FIG. 6 is an enlarged fragmentary view of the front grill;

FIG. 7 is cross-sectional view taken along line 7—7 of FIG. 6, and

FIG. 8 is a rear elevational view of the horn.

I claim:

The ornamental design for a marine horn, substantially as shown and described.
